UNITED STATES PATENT OFFICE.

ENOCH GEORGE, JR., OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA.

DRAFT-RIGGING.

1,301,680.

Specification of Letters Patent. Patented Apr. 22, 1919.

Application filed June 28, 1917. Serial No. 176,581.

To all whom it may concern:

Be it known that I, ENOCH GEORGE, Jr., a citizen of the United States, residing at Pittsburgh, in the county of Allegheny and State of Pennsylvania, have invented certain new and useful Improvements in Draft-Rigging; and I do hereby declare the following to be a full, clear, and exact description of the invention, such as will enable others skilled in the art to which it appertains to make and use the same.

My invention relates to draft rigging for railway cars and is particularly addressed to means for pivotally connecting the rear end of a drawbar to the front end of a yoke in a manner enabling the usual tail pin to be dispensed with. The principal object of the invention is to produce means of the character indicated which are simple in construction, strong, and practical and durable in service. Generally stated, the best mode in which I contemplate applying the principle of my invention to accomplish this object involves the combination of a drawbar having oppositely extending pivot lugs, a draft yoke having upper and lower branches that are respectively provided with sockets affording curved bearing faces adapted to engage the corresponding pivot lugs, and means for preventing separation of the branches of the yoke at their forward ends without interfering with the pivoting of the coupler or drawbar with respect to the yoke, such means preferably consisting of a sleeve embracing the rear end of the drawbar and the forward end of the yoke and having its opening flared or widened centrally to permit swinging of the drawbar with respect thereto.

In the drawing illustrating the invention, the scope whereof is pointed out in the claims,

Figure 1 is a plan view of an assembled mechanism embodying my invention, the springs and followers or other cushioning elements of the draft rigging commonly embraced by the yoke being omitted.

Fig. 2 is a side elevation of the devices illustrated in Fig. 1, the head of the coupler or drawbar being omitted.

Fig. 3 is a side elevation similar to Fig. 2, the sleeve member being in section to show the operative relation of the rear end of the drawbar and forward end of the yoke.

Fig. 4 is a detail plan view of the rear end of the drawbar illustrated in Figs. 1 and 2.

Fig. 5 is a detail plan view of the forward end of the draft yoke illustrated in Figs. 1 and 2.

Figs. 6 and 7 are, respectively, an end elevation and a horizontal central section of the sleeve member which embraces the rear end of the drawbar and the forward ends of the draft yoke branches.

Fig. 8 is a side elevation of a modified form of the rear end of the drawbar and forward end of the yoke, the sleeve being in section.

Fig. 9 is a detail plan view of the rear end of the modified form of drawbar and the forward end of the yoke shown in Fig. 8.

Fig. 10 is a detail side elevation showing in assembled relation a portion of a drawbar and draft yoke embodying a modification of the invention in which the sleeve member is not employed.

Fig. 11 is a detail plan view of the devices illustrated in Fig. 10.

Fig. 12 is a view corresponding to Fig. 10 and showing a further modification of the invention.

Fig. 13 is a detail plan view of the construction illustrated in Fig. 12.

In the construction illustrated in Figs. 1 to 5, inclusive, the drawbar 1 is provided near its rear end with oppositely disposed vertically extending pivot lugs 2 of frustoconical form, the smaller diameters of the lugs, as shown, being at their points of junction with the main body of the drawbar. These pivot lugs are preferably of comparatively sharp curvature in order to facilitate the turning of the drawbar with respect to the yoke, their diameters of curvature being preferably less than the width of the drawbar at this point. A short distance in advance of the pivot lugs 2 the drawbar is provided with a plurality of oppositely disposed vertically extending lugs 3. The rear-most face 4 of each lug 3 is inclined toward the center of the drawbar or undercut to cooperate with the correspondingly inclined or beveled forward end 5 of the adjacent limb or branch of the draft yoke 6; and each lug 3 is also preferably formed with an upright rearwardly facing shoulder 7 which is adapted to engage the sleeve member 8 at its forward end to thus limit the forward move-

ment of the drawbar. The forward end 5 of each lug 3 is also preferably formed with an upright rearwardly facing shoulder 7 which is adapted to engage the sleeve member 8 at its forward end to thus limit the forward move-

ment of said sleeve. The forward ends 5 of the draft yoke are curved as also are the end faces 9 of the sleeve which engage the stops 7; and the rearwardly facing shoulders 4 and 7 of the lugs 3 are also preferably curved correspondingly.

At its forward end each limb or branch of the yoke 6 is fashioned with a socket 10 which opens toward the rear and is adapted 10 to receive one of the pivot lugs 2. The forward face of each socket is curved and inclined so as to form a conical bearing surface 11 for the corresponding pivot lug 2. Extending rearwardly from these curved 15 bearing faces each socket 10 is fashioned with parallel side walls 12 which are sufficiently long to maintain the pivot lugs 2 always in place, thus insuring that the drawbar 1 and yoke 6 shall be in substantially 20 true alignment when cars are on straight track.

The sleeve member 8 surrounds the rear end of the drawbar 1 and the forward end of the yoke 6, preventing the branches of the 25 yoke from separating or spreading. The opening 13 through the sleeve member is wider centrally than at the top and bottom. The forward ends of the branches of the draft yoke project into the narrower portions of the opening 13, while the widened 30 central portion, which is preferably flared at the forward end, as at 14, accommodates the drawbar and enables it to swing freely from side to side with respect to the yoke 6.

35 In assembling the construction heretofore described the drawbar 1 and yoke 6 are turned at right angles to each other and the pivot lugs 2 are entered in the sockets 10 at the forward end of the yoke. The draft 40 yoke and drawbar are then rotated until they assume their normal alignment with each other, after which the sleeve 8 is slipped on the rear end of the yoke 6 and slid forwardly until it is arrested by coming in 45 contact with the upright shoulders or stops 7 on the drawbar. The followers and springs or other cushioning devices (not shown) may then be inserted between the branches of the yoke 6 as usual.

50 The modified form of drawbar and draft yoke shown in Figs. 8 and 9 are designed to be substituted for the drawbar 1 and yoke 6 and to be used in conjunction with the sleeve member 8. In this modified construction the pivot lugs 2^a of the drawbar 1^a are cylindrical instead of frusto-conical, and the shoulders or faces 4^a on the drawbar which coöperates with the forward ends of the yoke 6^a are vertical instead of undercut or beveled. The yoke 6^a for use with the drawbar 1^a differs from the yoke 6 previously described in that the forward ends 5^a of its branches are cylindrically curved instead of conical and the bearing faces 11^a thereof are 65 also cylindrical instead of conical surfaces.

The modified construction illustrated in Figs. 10 and 12 dispenses with the sleeve member 8 and provides other means for preventing separation of the forward ends of the branches of the yoke. In this form of 70 the invention the drawbar 15 is provided with oppositely disposed vertical pivot lugs 16 which are adapted to be received in correspondingly curved sockets 17 at the forward ends of the branches of a draft yoke 75 18 which is preferably of the same form as the yoke illustrated in Figs. 8 and 9. A short distance in advance of the pivot lugs 16 the drawbar 15 may be provided with curved vertically extending shoulders 19, 80 as shown in Figs. 10 and 11, which are respectively adapted to coöperate with the curved forward ends of the draft yoke 18 to thus limit the forward movement of the yoke with respect to the drawbar. Extending rearwardly from the outer end of each shoulder or stop 19 is a flange or plate 20 which overlaps the forward end of the adjacent branch of the draft yoke. These members 20, which are preferably the full width 90 of the draft yoke 18 and extend rearwardly far enough to overlie the pivot lugs 16, prevent the branches of the yoke from separating at their forward ends, thus performing that function of the sleeve member 8. The 95 drawbar 15 and draft yoke 18 of this modified construction are assembled by engaging the pivot lugs 16 with the corresponding bearing faces 17 of the yoke while the parts are positioned at right angles to each other, 100 and by then turning the drawbar and yoke until they come into alignment in their normal positions.

The modification illustrated in Figs. 12 and 13 is like the construction shown in 105 Figs. 10 and 11, except that the upright stop faces or shoulders which coöperate with the curved forward ends of the yoke are not curved but are vertically extending flat faces 21.

110 I claim:

1. In a draft rigging, the combination with a drawbar, of a draft yoke pivotally connected thereto, and a sleeve embracing said drawbar and yoke, said drawbar being 115 provided with means for engaging and limiting the forward movement of said sleeve, and the portion of said sleeve engaged by said limiting means being curved to permit said drawbar to have pivotal movement with 120 respect thereto.

2. In a draft rigging, the combination with a drawbar, of a draft yoke pivotally connected thereto, and a sleeve embracing said drawbar and yoke, said sleeve having 125 an opening therethrough which is widened to afford clearance permitting said drawbar and yoke to pivot upon each other.

3. In a draft rigging, the combination with a drawbar having vertically extending 130

5 pivot lugs adjacent its rear end, of a draft yoke provided with correspondingly curved bearing shoulders adapted to engage said pivot lugs, and a sleeve embracing said drawbar and yoke, said sleeve being formed with a flaring opening in which said drawbar is adapted to swing laterally.

10 4. In a draft rigging, the combination with a drawbar, of a draft yoke pivotally connected thereto, and a sleeve embracing said drawbar and yoke, the opening through said sleeve being wider centrally than at the top and bottom, the said drawbar extending into the wider portion of said opening, and 15 the narrower portions of said opening being adapted to receive the forward portions of said yoke.

20 5. In a draft rigging, the combination with a drawbar provided with vertically extending pivot lugs and having in advance of said pivot lugs a plurality of upright projections constituting means for limiting longitudinal movement of a draft yoke and a sleeve with respect to said drawbar, of a 25 draft yoke having upper and lower branches each of which is provided near its forward end with a curved bearing face adapted to engage the corresponding pivot lug of said drawbar, the forward ends of the branches 30 of said yoke being adapted to be engaged by the said upright projections, and a sleeve embracing said drawbar and yoke and adapted to engage said upright lugs.

35 6. In a draft rigging, the combination with a drawbar having vertically extending pivot lugs adjacent its rear end, of a draft

yoke having at its forward end a plurality of sockets respectively adapted to receive said pivot lugs, each of said sockets being open at the rear and having at its forward 40 end a curved bearing face adapted to engage one of said pivot lugs and being formed with side walls extending rearwardly from said curved bearing face and adapted to receive one of said pivot lugs between them, 45 and means rearwardly movable with respect to said yoke for preventing separation of the socketed ends of said yoke.

50 7. In a draft rigging, the combination with a drawbar, of a draft yoke pivotally connected thereto, one of said members being formed with a curved pivot lug whose diameter of curvature is less than the width of the part on which it is formed, and the other of said members being formed with 55 a socket open at one end and having a curved bearing face adapted to engage said curved pivot lug, and a sleeve encircling said yoke for preventing separation of the forward ends of said yoke. 60

8. In a draft rigging, the combination with a drawbar having a pivot lug and a stop lug in advance of the pivot lug to limit the forward movement of the yoke with respect to the drawbar, of a yoke having a 65 socket for the reception of the pivot lug, said socket being open at its rear and provided with parallel walls preventing lateral displacement of the pivot lug of the drawbar. 70

In testimony whereof I affix my signature.
ENOCH GEORGE, JR.
